CIGARETTE HOLDER

Elbert Orson Brower, Philadelphia, Pa.

Application November 23, 1934, Serial No. 754,452

3 Claims. (Cl. 131—10)

My invention relates to holders for cigarettes, and has for its object, the production of a simple and efficient device.

In the accompanying drawing

5 Fig. 1 is an elevation of a holder with a cigarette supported thereby;

Fig. 2 is a longitudinal section of the holder at a larger scale;

Fig. 3 is an end elevation of Fig. 2;

10 Fig. 4 is the same as the right hand end of Fig. 2, but with the elastic band moved back to its inoperative position;

Fig. 5 is a longitudinal section of the elastic band removed from the holder, these sections 15 being parallel to a side of the square perimeter, not diagonally thereto; and

Fig. 6 illustrates a method of applying a cigarette and holder to each other.

The holder consists of a stem 10 and an elastic 20 ring or a band 11. The stem may be of wood, amber, pipe clay or any other suitable material. It has a central longitudinal opening 12 for smoke. The exterior may be of any form desired. The end part 13 upon which the ring or band is mounted, is cylindrical, and terminates 25 in a shoulder 14.

The band 11 is of rubber or other suitable material, and has a tapered opening 15 there thru, the larger diameter of which is slightly 30 less than the diameter of the cylindrical part 13. A consequence of this construction is that when the band is mounted upon its seat, it is under 35 elastic tension which acts to expand its diameter.

35 A longitudinal section of the band shows that the material thereof is roughly triangular. The exact proportions are not material, but those shown in Fig. 5 are satisfactory. The triangle here involved has annular edges or corners 16, 40 17 and 18. When the band is on its seat, the annular edge 16 comes against the shoulder 14, and the maximum tension is at the annular edge 17.

With the band located as shown in Fig. 2, a 45 pressure on the face 17—18 toward the left will cause the material of the band to turn on the annular edge 16 from the position shown in Fig. 2 to the position shown in Fig. 4. In this movement, the material of the band at and near the 50 edge 17 passes thru an intermediate stage or condition of greater tension than exists in either the position of Fig. 2 or the position of Fig. 4. In other words, the positions shown in Figs. 2 and 4 are positions of rest, between which the 55 band may be moved by hand. At any point be-

tween those two positions it is under greater tension and tends to move by snap action to one or the other of its positions of rest.

The face 17—18 may be considered as a flange 5 on an elastic clamping device. The perimeter 18 may be a circle, but is preferably made rectangular as shown in Fig. 3. One object of this is to prevent the holder from rolling when laid down. Another object of the form and construction shown, is, that by having the holder slightly heavier than the cigarette, the holder, when laid down will support a lighted cigarette above and clear of the surface of a table or other object upon which the holder may be laid.

Fig. 6 illustrates a way of applying the cigarette 15 20 to the holder 10 when the paper of the cigarette is slightly crumpled, and also illustrates a tooth 21 on the holder which may be used either for helping to reshape the crumpled paper, or for releasing a little of the tobacco when it is 20 packed too closely to the end of the paper to permit the insertion of the holder. In this view, the band 11 is in the position shown in Fig. 4. To smooth the paper, the cigarette is rotated 25 on its axis until the paper of the cigarette slips easily on the part 13. Then, by pressing the band to the right, the surface 16—17 clamps the paper to the surface 13.

It may be remarked that the shoulder 14 is a convenience rather than a necessity, as the 30 band 11 will operate in the same way on a plain metallic tube. But with an unsymmetrical band such as 11, greater pressure is involved in pushing it between positions of rest in one direction 35 than in the other direction, and this greater pressure causes a slight creep of the band on a smooth surface in the direction of the greater pressure. The shoulder 14 prevents such creep, and thus avoids the necessity for occasional adjustments.

40 What I claim is:

1. A stem having a shoulder near one end and an elastic band under tension on said stem, said band having a position of rest on either side of said shoulder, between which extreme positions 45 the band is manually movable by rolling the same about one of its marginal edges and thereby causing it to pass thru an intermediate condition of greater tension, and in one of which positions of rest the band is adapted to clamp an 50 end of a cigarette wrapper thereunder.

2. In a device of the class described, a band 55 of resilient material which is roughly triangular in cross section, and a tube upon which the band is mounted and under elastic tension with one

of the sides of the triangle in contact with the periphery of the tube, said band being manually movable on the tube to bring a different side in contact therewith to clamp an end of a cigarette wrapper thereon.

5. A tube having an exterior annular shoulder near one end, and an unsymmetrical band of

resilient material under tension and having an edge adjacent to said shoulder, said band being shiftable on said tube by a pivotal movement on said edge to clamp an end of a cigarette wrapper between the tube and the encircling band.

ELBERT ORSON BROWER.
